UNITED STATES PATENT OFFICE

RUFUS C. FINCH, OF RUMSON, NEW JERSEY

DESIGN FOR A TRAY HOLDER

Application filed December 9, 1929. Serial No. 33,716. Term of patent 14 years.

To all whom it may concern:

Be it known that I, RUFUS C. FINCH, a citizen of the United States and a resident of Rumson, county of Monmouth and State of New Jersey, have invented a new, original, and ornamental Design for Tray Holder, of which the following is a specification, reference being had to the accompanying drawing, forming part hereof.

I claim:
The ornamental design for a tray holder,
as shown.

RUFUS C. FINCH.
